UNITED STATES PATENT OFFICE.

MAX SAKOWSKI, OF MASSILLON, OHIO.

ARTIFICIAL LIMB.

1,267,121.

Specification of Letters Patent. Patented May 21, 1918.

Application filed December 26, 1917. Serial No. 208,821.

To all whom it may concern:

Be it known that I, MAX SAKOWSKI, a citizen of Russia, having declared my intention to become a citizen of the United States 5 of America, residing at Massillon, in the county of Stark and State of Ohio, have invented certain new and useful Improvements in Artificial Limbs, of which the following is a specification.

10 The primary object of the invention is the provision of an artificial upper-limb adapted to be comfortably worn by a person whose arm has been amputated at or near the shoulder, a hand member being provided 15 having adjustable fingers for grasping objects when desired.

A still further object of the device is to provide an artificial arm and hand that may be readily worn by a person and is light in 20 weight and is serviceable for soldiers whose arms have been amputated.

In the drawings forming a part of this application and in which like designating characters refer to corresponding parts 25 throughout the several views,

Figure 1 is a perspective view of the device.

Fig. 2 is a perspective view of the upper-arm member detached showing the lower 30 side thereof.

Fig. 3 is a perspective view of the upper end portion of the lower-arm detached member.

Fig. 4 is a plan view of the back of the 35 hand.

Fig. 5 is a plan view of the palm thereof.

Fig. 6 is a longitudinal sectional view through the hand and the wrist portion of the arm.

40 Fig. 7 is a detail view partially in section of the adjustable elbow joint.

Fig. 8 is a perspective view of one of the catch springs employed with the finger members, and

45 Fig. 9 is a perspective view of a portion of the finger operating means detached.

Referring more in detail to the drawing the device broadly consists of an artificial upper-limb 10 having a hand 11 fore-arm 12

50 and upper-arm 13, the device being adapted for attachment to the shoulder of the person by means of an inclosing harness 14 at the free end of the upper-arm 13 provided with cords 15 for connecting the shoe with a flexi-

ble pad 16 having a central opening 17 through which the other arm of the individual is positioned.

The fore and upper arms 12 and 13 are connected together by an elbow joint 18 in the form of a hinge, the upper arm having 60 a disk member 19 pivoted within a slot 20 in the upper end of the fore-arm by means of a pivot pin 21.

The disk 19 is provided with sockets 22 adapted to receive a spring pressed bolt 23 65 carried by the upper end of the fore-arm and normally projected within the slot 20 thereof. A slide plate 24 is arranged upon the back of the fore-arm 12 connected with the bolt 23 by means of a pivoted lever 25, 70 an upward sliding movement of the plate 24 being adapted for retracting the bolt 23 from the sockets 22 and into which the bolt automatically drops when the arm is either outstretched as shown in Fig. 1 of the draw- 75 ings or bent at the elbow as indicated by dotted lines in Fig. 7 thereof. In this manner, the device may be readily attached and worn by a person and the arm locked temporarily either in its outstretched or bent 80 arrangement.

The hand 11 has a body portion 26 with four fingers 28 hinged to the palm 29 thereof by means of hinges 30. A passage 31 is arranged through the hand body 26 for each 85 of the fingers registering with a chamber 32 in each of the fingers 28 and terminating at 33 in the lower side of the wrist portion 34 of the device. An angular lever 35 is connected by means of a rigid link 36 with 90 each of the fingers 28 within the said passage 31 and chamber 32 thereof while a slide block 37 is arranged upon the wrist 34 secured to the outer end of the lever 35.

By this arrangement, a movement of the 95 block 37 toward the hand 11 forces the rigid link 36 forwardly and by reason of its pivotal attachment to the outer side of the adjacent finger 28, such finger will be bent or swung upon its hinge 30 inwardly toward 100 the palm 29 as best illustrated by dotted lines in Fig. 6 of the drawings. A catch spring 38 is arranged in each slot 33 having a shoulder 39 for resiliently engaging the forward edge 40 of the adjacent block 37 105 when the block is forwardly positioned with the finger in bent relations. A rubber band or strip 41 is connected to the back of the

hand body 26 and the forward section 42 of each of the fingers 28 for returning the said fingers substantially outstretched in their normal arrangement when the blocks 37 are 5 released from the springs 38 by inwardly pressing upon the finger posts 43 with which each of the said springs is provided.

Hinges 44 are arranged at the backs of the fingers 28 for connecting the free end 10 portions 42 thereof with the main portions of the fingers 28, these hinges 44 underlying the bands 41. A cord or wire 45 is provided for each of the fingers 28 passing through the chamber 32 thereof over a trans- 15 verse pin 46 arranged therein, one end of the said cord 45 being attached as at 47 to the hand body 26 within the passage 31 thereof while its opposite end passes through a perforation 48 in the finger and is attached 20 as at 49 to the adjacent end of the forward joint or section 42 thereof.

When one of the blocks 37 is moved forwardly and engaged with its respective spring 38, the finger 28 which is attached 25 to such block by means of a lever 35 and link 36 will be folded against the action of the band 41 moving inwardly upon its hinge 30 while the action of the cord 45 will be to inwardly bend the free end section 42 of the 30 finger inwardly toward the palm 29 of the hand 11. A serviceable construction is provided which may be readily worn by the person and bent upon the elbow joint 18 and retained either bent or outstretched while 35 the fingers of the hand may be readily manipulated by the other hand of the wearer for grasping objects, the said fingers being automatically released upon operating the catch springs 38.

40 What I claim as new is:—

1. In combination with an artificial arm having a wrist portion, a hand carried thereby having fingers hingedly arranged upon the hand with passages through the hand 45 extending into the fingers and terminating in slots through the wrist portion of the arm, sliding blocks upon said wrist, operating connections between the said blocks and fingers within said passages, spring retainers for the said blocks, releasing means for 50 said retainers, resilient returning bands for the said fingers, and free end portions for the fingers operatively connected to the hand within the passages therethrough whereby 55 the fingers are inwardly foldable toward the palm of the hand upon moving the said blocks toward the hand.

2. An artificial arm comprising a hand and wrist portion having a passage there- 60 through terminating in a slot in the wrist portion, fingers hinged to the hand portion for movement toward the palm thereof, means for moving the fingers toward the palm extending through said passage and 65 said slot and pivoted to the fingers, releas-

able catch means for said moving means, resilient means for substantially straightening the fingers when released, a free end portion hinged to each finger, and connec- 70 tions between said free end portions and the hand within said passage thereof whereby said free end portions are caused to move toward the palm of the hand when the fingers are swung upon their hinges.

3. In combination with an artificial arm 75 having a wrist portion, a hand carried thereby having fingers hingedly arranged upon the hand with passages through the hand extending into the fingers and terminating in slots through the wrist portion of the 80 arm, sliding blocks upon said wrist, operating connections between said blocks and said fingers within said passages, spring retainers for said blocks, releasing means for said retainers, and resilient returning means for 85 said fingers.

4. In combination with an artificial arm having a wrist portion and a hand portion, finger members hingedly carried by said hand portion, end members hingedly carried by said finger members, rods hingedly connected to said finger members and extending to a point adjacent said wrist portion, forwardly slideable means at said wrist portion and connected to said rods for 95 swinging said finger members toward the palm of the hand portion, means for retaining said finger member swinging means in its forward position, resilient means connected to the back of the hand portion and 100 to the end members to normally maintain the finger members and the end members in substantially straightened position, and means connected to the hand portion and to the end members to cause the latter to swing 105 toward the palm of the hand portion when the finger members are swung toward the palm of the hand portion.

5. In combination with an artificial arm having a wrist portion and a hand portion, 110 finger members hingedly carried by said hand portion, end members hingedly carried by said finger members, said hand portion and finger members having passages therethrough, rods hingedly connected to said 115 finger members and extending through the passages in said hand portion to a point adjacent said wrist portion, forwardly movable means extending through said wrist portion and connected to said rods for swing- 120 ing said finger members toward the palm of the hand portion, means for retaining said finger member swinging means in its forward position, resilient means connected to the back of the hand portion and to the 125 end members to normally maintain the finger members and the end members in substantially straightened position, and means connected to the hand portion and to the end members to cause the latter to swing to- 130

ward the palm of the hand portion when the finger members are swung toward the palm of the hand portion.

6. In combination with an artificial arm, having a hand portion, finger members hingedly carried by said hand portion, end members hingedly carried by said finger members, means for swinging said finger members toward the palm of the hand portion, and

means connected to the hand portion extending through the finger members and connected to the end members to cause said end members to swing independently of the finger members toward the palm of the hand portion when the finger members are swung 15 toward the palm of the hand portion.

In testimony whereof I affix my signature.
MAX SAKOWSKI.
